3,165,855 AUTOMATIC CASTING ROD WITH LINE GRIPPING MEANS

James R. Stephenson, Kettering, Ohio; Carl M. Stephenson, administrator of said James R. Stephenson, deceased

Filed Apr. 17, 1961, Ser. No. 193,308
14 Claims. (Cl. 43—19)

This invention relates to an automatic casting rod and more particularly to a fishing rod adapted to automatically carry out the ordinary manual operations performed by a fisherman in casting out his line; however, the invention is not necessarily so limited.

The present application is a continuation-in-part of my copending application Serial No. 22,216, filed April 14, 1960, for an Automatic Casting Rod.

In the ordinary casting operation a fisherman attaches a weight to a line which is supplied from a spinning or casting reel. Holding the line tight with his finger or thumb, the fisherman then swings his rod overhead through a swiftly executed circular arc to give the weight attached to the line an outward momentum. Near the end of the circular arc the fisherman releases the line, permitting the momentum of the weight to carry the line out away from the rod. Where a casting reel is used the fisherman manually takes up the momentum of the reel as the outward motion of the weight fades. This prevents overspin of the reel. Where a spinning reel is used, the reel itself does not rotate and therefore acquires no momentum and no manual braking of the device is required.

In the past numerous automatic mechanisms have been designed for carrying out the casting operation. In general, these mechanisms rely upon an abrupt swinging movement of the fishing rod which is produced by a spring or similar mechanism. A problem common to all of these devices is the problem of securing the weight in such a manner that it will acquire momentum during the initial swinging movement of the rod, but will be released just prior to the end of the arcuate swing of the rod. If the weight is not properly secured at the beginning of the swing, the fishing line merely dewinds from the spinning or casting reel and the weight acquires no outward momentum. On the other hand, if the weight is not released prior to the end of the swing, part of its momentum is lost as the swing terminates and an erratic casting operation results.

An object of the present invention is to provide an automatic casting device including means for anchoring the weight at the commencement of the casting movement and for releasing the weight prior to the end of the casting movement. Another object of the present invention is to provide an improved trigger mechanism for controlling the operation of the casting rod.

Still another object of this invention is to provide an improved spring actuated mechanism for operating an automatic casting fishing rod.

Other objects and advantages reside in the construction of parts, the combination thereof, the method of manufacture and the mode of operation, as will become more apparent from the following description.

In the drawings,

FIGURE 1 is a fragmentary perspective view illustrating two positions of the automatic casting rod.

FIGURE 2 is an enlarged fragmentary plan view of the operating mechanism of the casting rod.

FIGURE 3 is an enlarged fragmentary side elevational view of the operating mechanism of the casting rod with parts shown in section.

FIGURE 4 is a greatly enlarged perspective view of

a line clamping mechanism employed in the present invention, parts being shown in phantom detail.

FIGURE 5 is a greatly enlarged sectional view illustrating one mode of operation of the line clamping means of FIGURE 4.

FIGURE 6 is an enlarged exploded view illustrating structural details of the operating mechanism.

FIGURE 7 is a fragmentary perspective view illustrating two positions of a modified casting rod.

FIGURE 8 is an enlarged perspective view of the modified casting rod with portions broken away and other portions shown in exploded detail.

FIGURE 9 is an enlarged perspective view illustrating a modified line clamping mechanism in disassembled detail.

FIGURE 10 is an end elevation view with parts shown in section illustrating the operation of the line clamping mechanism of FIGURE 9.

Referring to the drawings in greater detail, a fishing rod having a handle 10 and a rod portion 12 is illustrated in FIGURE 1. The handle and the rod portion are pivotally joined by a mechanism best illustrated in FIGURES 3 and 6.

Turning attention to FIGURE 3, it will be observed that the handle 10 terminates toward the left end of the figure in a block portion 14. In FIGURE 6, it will be seen that a plurality of screws 17 secure plates 15 and 16 to opposite sides of the block portion 14. Positioned between the plates 15 and 16 is a sprocket wheel 18 journaled on an axle 20. This axle is tubular and is secured by screws 19 passing through the plates 15 and 16 and threaded internally of the axle 20. The sprocket wheel 18 has oppositely disposed circular bosses 18a which fill the space between the plates 15 and 16.

The rod portion 12 terminates in a cylindrical cap portion 21 to which is fixed a substantially solid shaft 22. As best illustrated in FIGURE 6, the shaft 22 terminates at its inner end with a large projection 23 and smaller spaced projections 24a and 24b. These projections cooperate to provide a channel for receiving the periphery of the sprocket wheel 18. The latter is fixedly secured to the projections by pins 25. Through this means the rod portion 12 is fixed to the sprocket wheel 18. Since the sprocket wheel 18 is rotatable relative to the handle 10, the rod portion 12 is pivotable relative to the handle 10.

The pivotal movement of the rod portion 12 in a counter-clockwise direction as illustrated in FIGURE 3 is limited by a pin 26 passing through the sprocket wheel 18 which engages complementary seats 27 formed in the block portion 14. The pin 26 cooperates with the seats 27 to locate the rod portion 12 in a rest position for ordinary fishing operations.

As illustrated in FIGURE 3, the sprocket wheel 18 is biased to the rest position by an elongate spring 28 which acts upon a link chain 30 adapted to nest in the teeth of the sprocket wheel 18. The terminal link 31 of the chain 30 is permanently secured to the sprocket wheel 18 by means of the pin 34.

As illustrated in FIGURES 3 and 6, the chain 30 passes through a central bore 29 in the block portion 14 into a sleeve 32 in the interior of the handle 10. The chain 30 is connected to the spring 28 by means of an elongate rod 36 anchored at one end to the chain 30. At its opposite end the rod 36 passes through a washer 42 where it encircles a transverse pin 38. The pin 38 has a length slightly less than the diameter of the sleeve 32 and thereby secures the rod 36 against movement through the washer 42. The spring 28 is compressed between the washer 42 and the block portion 14.

A chain and sprocket construction of the type disclosed herein offers the advantage that a substantially pure rota-

tional torque is applied to the sprocket. Thus, substantially all the force of the spring 28 is applied to the sprocket at the point of separation between the chain and the sprocket, a point vertically below the rotational axis of the sprocket, as viewed in FIGURE 3. With such construction radial loads on the axle 20 are minimized.

According to the foregoing construction, it is evident that upon clockwise movement of the rod portion 12 relative to the handle 10, the spring 28 is compressed. Latch means are employed to lock the rod portion 12 at any desired point in its pivotal movement relative to the handle 10. This latch means comprises a trigger member 44 which, as best seen in FIGURE 6, is formed of parts 44a, 44b, and 44c laminated together and secured by rivets 45. This trigger member is pivoted on an axle 46 journalled between the plates 15 and 16 and carries a transverse rod portion or detent 48 adapted to latch in any of the notches in the sprocket wheel 18.

The central laminated part 44c of the trigger member projects upwardly into a longitudinal channel (not shown) in the block portion 14 where it is acted upon by a spring 47 seated in a bore 49 formed in the block portion 14.

The spring 47 applies a sufficient bias to the trigger member 44 to anchor the sprocket wheel against counter-clockwise movement (as viewed in FIGURE 3) in any selected position. On the other hand, the trigger member is so arranged angularly with respect to the periphery of the sprocket wheel that the detent 48 carried thereby is automatically cammed out from between the teeth of the sprocket wheel on clockwise movement thereof. Thus, the rod 12 may be cocked to any desired position without interference from the latch mechanism. Once cocked, the latch mechanism will automatically lock the rod in place. Upon subsequent retraction of the trigger member, the spring 28 will operate to force the rod to its rest position.

This forced pivotal movement of the rod portion 12 from its cocked position to its rest position simulates an ordinary casting movement. As emphasized hereinbefore, however, such movement will be effective to cast a weight and associated line only when the weight is carried by the rod portion during the initial portion of the movement. Means for securing the weight are described in the following.

Fixedly mounted on the shaft 22 associated with the rod portion 12 is a loop member 50. A complementary loop member 52 is pivotally secured adjacent the loop member 50. For this purpose the loop member 52 has a downwardly extending shaft 53 journalled in a suitable transverse aperture in the shaft 22. Internally of the shaft 22, shaft 53 carries a pinion 54, best seen in FIGURE 4. This pinion is engaged by an actuating rack 56 mounted in an axially extending bore 55 in the shaft 22 and slidable outwardly thereof between the projections 24a and 24b.

The rack 56 is biased outwardly by means of a spring 58 seated in the bore 55. As illustrated in FIGURE 3, the rack 56 is located to one side of the sprocket wheel 18 and is biased against the periphery of an arcuate cam 62 fixedly secured to the plate 16 by a screw 60.

With the rod portion 12 in its rest position, as illustrated in FIGURE 3, it will be observed that the actuator rack 56 engages the outer periphery of the cam 62 and in such position the rack 56 holds the loop member 52 at substantial right angles to the loop member 50. When the rod portion 12 is pivoted in a clockwise direction, as illustrated in FIGURE 3, the rack 56 drops off the cam 62 and advances inwardly under force of the spring 58 until the loop member 52 pivots into parallel clamping relation to the fixed loop member 50. As will be described in greater detail subsequently, the loop members 50 and 52 in this position function to secure a fishing line passing therebetween. Upon counterclockwise movement of the rod portion 12 from a cocked position to its rest position, there is initially lost rotary motion as the rack 56 slides along the periphery of the boss 18a toward the cam

62, then the rack 56 engages the cam and is forced to move outwardly to the outer periphery thereof, thereby releasing the line clamped between the loop members 50 and 52. To facilitate this movement, the rack 56 has a beveled portion 64 adapted to follow an end wall 63 of the cam 62. This structure is best illustrated in FIGURE 4.

It will be noted that by proper positioning of the cam 62, the angle of the rod portion 12 relative to the handle 10 at which the loop members 50 and 52 separate to release the line passing therethrough may be set to any desired value.

For the purpose of illustration, a spinning reel 70 is shown mounted on the handle 10. This spinning reel supplies the fishing line 72 which may be of any conventional type. As shown, the line 72 is threaded through guiding eyelets 73, located at spaced intervals along the rod 12, which confine the line 72 to a path extending along the rod 12. In practice, the fisherman usually attaches a leader 74 to the fishing line. The leader is ordinarily much stronger than the line itself and has the primary function of reducing the opportunity of a fish to abrade or otherwise weaken the line.

In the present invention, the leader 74 may be used advantageously to perform another function. If the length of the leader is somewhat longer than the overall length of the rod portion 12, the knot 76 which is ordinarily formed when the leader is joined to the fishing line may be so located that it lies adjacent but slightly inside of the loop members 50 and 52 when the line is reeled in for casting operation. Under such circumstances, the knot will function to positively lock the line between the loop members 50 and 52 when these members are positioned to clamp the line. This locking condition is illustrated in FIGURE 5.

FIGURE 5 illustrates the line 72 and leader 74 passing through the loop member 52 such that when the loop members 50 and 52 are in parallel engaging position the line is necessarily clamped therebetween. In this regard it will be noted that the central apertures in the loop members 50 and 52 are of equal diameter such that the loop members have aligned inner margins when disposed side by side. This minimizes the possibility that the knot will work in between the loop members and force them apart. FIGURE 5 illustrates the line passing through the loop 52. As a result, line movement is virtually unobstructed after the loop 52 has pivoted to the position illustrated in FIGURE 3.

While the formation of a positive lock through the medium of a knot in the fishing line has been discussed in connection with the present invention, it is to be understood that a positive lock such as obtained with a knot can be obtained with other types of bulges formed in the line.

FIGURES 7 through 10 illustrate a modified casting rod comprising a handle 100 and a rod 102. The mechanism for pivotally joining the rod to the handle is best illustrated in FIGURE 8. There it will be noted that the handle 100 includes an elongate tubular housing 104 closed at one end as illustrated at 105. Near the center of the handle, the casing 104 is encircled by a pair of spaced ferrules 106 and 108. The former is fixedly secured to the handle by a screw 110, and the latter is slidably adjustable on the casing by means of a ring nut 112 threadedly engaging the casing. These ferrules 106 and 108 cooperate to clamp the base 114 of a suitable casting reel or spinning device, not shown. On either side of the ferrules 106 and 108 the casing 104 is covered with sleeve members 116 and 118 for ornamentation.

A pair of spaced generally circular plates 120 and 122 are welded to the open end of the casing 104. For adequate bearing support, the plates 120 and 122 have portions 124 and 126 projecting into the open ends of the casing. These plates are each provided with a central aperture. An internally threaded socket element 130 pro-

jects through the aperture in the plate 120, and a screw element 128 threadedly engaging the socket element 130 projects through the aperture in the plate 122. A bearing 132 is mounted on the socket element 130 between the plates 120 and 122, and these plates are drawn tightly against the ends of the bearing by means of the screw 128. The length of the bearing 132 thereby determines the separation between the plates 120 and 122.

A sprocket member 134 having notches 136 therein is mounted for rotation upon the bearing 132 between the plates 120 and 122. The fishing rod 102, provided with a metallic end piece 150, is secured to the sprocket member through the medium of an adapter 152 fastened to the sprocket member with suitable fasteners 154. The arrangement is such that the rod 102 may be pivoted relative to the handle 100 through rotation of the sprocket member 134 on its bearing 132.

A chain 138, having its terminal link secured to the sprocket member 134 at 140, extends from the sprocket member into the casing 104. Internally of the casing at 139, the chain engages a rod 142 which terminates in a threaded portion receiving a nut 145 securing a washer 144 on the rod. An elongate spring 146 encircles the rod 142 and the chain 138, one end of the spring engaging the washer 144 and the opposite end of the spring engaging the portions 124 and 126 of the plates 120 and 122. The tendency of the spring 146 to expand places a clockwise torque on the sprocket member 134, as viewed in FIGURE 8.

The rotational position of the sprocket wheel 134 is governed by a trigger member illustrated generally at 160. This trigger member, which is preferably although not necessarily formed in one piece with heavy gauge sheet metal, includes an upwardly directed folded portion 164 which supports a detent member 166 between the opposite sides thereof. As will be described hereinafter, the detent 166 is adapted to engage various notches 136 in the sprocket member 134. The trigger member is pivoted on a screw element 162 engaging the plates 120 and 122 so as to enable movement of the detent 166 into and out of engagement with the notches of the sprocket wheel.

The trigger member also includes an integral lever portion 172 extending substantially at right angles to the portion 164 rearwardly along the handle. This lever is used to manually pivot the trigger member. Extending oppositely from the lever 172 is an arm portion 168 adapted to engage a stop 170 mounted on the sprocket wheel 134. Due to the torque applied to the sprocket member 134 by the spring 146, the stop 170 acts on the arm 168 so as to urge the trigger member in a counterclockwise direction as viewed in FIGURE 8. Thus, the stop 170, acting on the arm portion 168, urges the detent 166 away from the periphery of the sprocket wheel and also presses the lever 172 against the handle 100. Preferably, the sleeve 118 mounted on the handle casing 104 is provided with a suitable recess 174 which receives the lever 172, thereby enabling the lever 172 to move to a position flush with the surface of the handle. A spring 176, situated within a suitable housing 178 supported between the plates 120 and 122, biases the trigger member 160 in a clockwise direction in opposition to the bias applied by the stop member 170 associated with the sprocket wheel 134.

The operation of the trigger member is as follows. When the fishing rod is pivoted in a counterclockwise direction as viewed in FIGURE 8 the sprocket member 134, acting through the medium of the chain 138, compresses the spring 146. As the stop 170 on the sprocket wheel 134 moves away from the arm 168, the spring 176 becomes effective to bias the trigger member 160 in a clockwise direction so as to urge the detent 166 carried by the trigger member against the periphery of the sprocket wheel. With continued counterclockwise movement of the sprocket member 134, the detent 166 cams away from

successive notches in the sprocket wheel due to the shape of these notches. However, as soon as counterclockwise rotation of the sprocket wheel ceases, the detent 166 drops into the closest notch 136 and holds the sprocket member in its cocked position. When the detent 166 is in this position, the lever 172 is pivoted upwardly away from the handle, as shown in FIGURE 7. If the lever 172 is then manually depressed against the handle 100, the detent 166 is disengaged from the sprocket wheel and the spring 146 becomes effective to pivot the rod 102 to its rest position which is substantially parallel to the handle 100. When the rod 102 reaches its rest position, the stop 170 on the sprocket member engages the arm 168 associated with the trigger member, thereby stopping further clockwise rotation of the sprocket member 134 and forcing the lever 172 to its position flush with the decorative sleeve 118 on the handle 100.

From the foregoing, it is apparent that the mechanism described enables pivotal movement of the rod 102 to a cocked position. Upon actuation of the lever 172, the spring 146 acts to drive the rod 102 violently to a rest position parallel with the handle 100. As discussed in connection with the first embodiment, this pivotal movement of the fishing rod can be employed to effect a casting operation. However, as was the case in the first embodiment, it is necessary for satisfactory casting to provide some means for clamping the fishing line during the casting stroke until the rod is very nearly in its rest position. Since monofilament lines are conventionally used in casting equipment, the difficulties in gripping the line are particularly acute. Thus, monofilament lines are susceptible to injury from pressure. It is therefore preferable to grip the line with a gentle pressure applied over a large area in a controlled fashion.

As part of the mechanism for clamping the line, an arcuate cam 180 is secured to the sprocket wheel 134 by suitable fastening members 182. The outer curved surface of this cam is disposed substantially concentric to the axis of rotation of the sprocket member. It would be possible, of course, to use this cam to operate a line engaging means of the type disclosed in the first embodiment. However, in the present embodiment, this cam is used to operate a different type of line engaging means.

This line engaging means includes a generally cubical housing 184 provided with oppositely disposed lugs 198 and 202. The housing 184 rests against the outer face of the plate 122, the lug 198 being provided with an aperture 200 through which the screw 128 passes and the lug 202 being secured to the outer margin of the plate 50 122 with a screw 204.

As illustrated in FIGURE 9, the housing 184 is partitioned by a fixed wall portion 186. This wall 186 and the opposite sides of the housing 184 are apertured so as to receive an elongate flexible, preferably elastomeric, tube 188 passing through the housing. The aperture in the wall 186 is slightly smaller than the diameter of the tube 188 such that this wall holds the tube in position. The apertures 187 and 189 in the housing 184 are larger than the diameter of the tube 188 so as to permit free movement of the ends of the tube.

A cam follower element 190 fits in the base of the housing. This cam follower element is provided with a pair of lugs 192 which straddle the wall portion 186. On the opposite side of the cam follower element is a lug 65 194 which projects through a rectangular window 196 in the plate 122 to engage the cam 180 on the sprocket member 134.

The construction is such that when the rod 102 is in its rest position, the lug 194 on the cam follower is disengaged from the cam 180 and the lugs 192 on the cam follower project into the housing 184 adjacent the tubing 188. When the rod 102 is pivoted to a cocked position, an inclined surface 206 on the cam 180 engages the lug 194 on the cam follower and moves the cam follower upwardly in the housing 184, as viewed in FIGURES 8 and 75

9. As the cam follower moves upwardly in the housing, the lugs 192 engage and distort or kink the tubing 188. FIGURE 10 illustrates the distorted condition of the tubing 188 when the rod 102 is in the cocked position such that the lug 194 on the cam follower engages the outer curved surface of the cam 180. In this figure, a fishing line 210 is included to show how the line is gripped by the tube 188.

In the distorted condition, portions of the tube 183 on opposite sides of the wall 186 are forced upwardly against the top of the housing causing the inner wall of the tube to compress slightly the line 210 in the distorted condition. The center and outer ends of the tube are bent angularly when the tube is distorted, insuring that the inner wall of the tube will press against the line 210 along substantially the entire length of the line within the housing.

184. It is important to note that the line is both compressed and distorted or curved out of its straight line condition in the present embodiment. It is found that mere compression in the absence of distortion requires a much greater compressive force than is required when there is both compression and distortion. In the latter case, the force delivered to the tube through the medium of the lugs 192 need not be as large and the possibility of damage to the fishing line is minimized. Further, this enables use of relatively inexpensive plastic parts. When the housing 184 and cam follower 190 are of plastic construction, the cam follower lug 194 may be provided with a metal tip, not shown, to reduce frictional wear caused by repeated sliding contact between this lug and the cam.

In operation of the casting device, the fishing line 210 which emerges from a suitable casting reel or spinning device is passed through the flexible tube 188 and then through the various eyelets on the fishing rod to the outer end of the fishing rod. Beyond the end of the fishing rod, a suitable weight, not shown, may be secured to the line. When the rod 102 is pivoted to a cocked position, the flexible tube 188 is distorted, as shown. When the lever 172 is depressed enabling the spring 146 to return the rod to its rest position, the fishing line 210 remains clamped in the flexible tube 188 until the lug 194, associated with the cam follower 190, drops down the surface 206 on the cam 180. The natural resiliency of the flexible tubing 188 then causes the tubing to straighten itself, providing a free path for movement of the line therethrough. When this free path exists, the momentum associated with the weight secured to the line carries the weight away from the rod as in the ordinary manual casting operation.

From the foregoing discussion, it is apparent that the present casting mechanism simulates very closely the manual operations carried out by a fisherman who casts with conventional equipment including a spinning reel. When a casting reel is used rather than a spinning reel, it is necessary for the fisherman to brake the momentum of the casting reel in the usual manner; however, the present casting mechanism is otherwise fully automatic.

It is to be observed that the particular construction of the present device enables the use of a comparatively long compression spring for accomplishing the casting operation. A long spring of this type offers the advantage that the casting movement is smooth and steady. Where a short spring must be used, the amplification of motion between the spring and the rod must be increased with the result that the movement of the fishing rod becomes abrupt and there is no steady casting movement.

As illustrated in the present embodiment, the sprocket member 134 need not have uniformly spaced notches throughout its entire periphery. It is preferable, of course, that the sprocket member have notches uniformly spaced over that portion of the periphery which will be engaged by the chain 138. As illustrated in FIGURES 1 and 7, the rod is ordinarily pivoted about 90° to the

cocked position. Accordingly, the chain will ordinarily contact only about 90° of the sprocket. Beyond that portion of the periphery, the notches need not be uniformly spaced and no notches are required in the vicinity of the adapter 152. As illustrated in FIGURE 8, the notches in the periphery of the sprocket member 134 above the adapter 152, as viewed in FIGURE 8, may be more widely spaced, these notches serving only to locate various cocked positions for the rod 102. It is preferable to increase the spacing between notches and to make the teeth formed by the notches larger in this area of the sprocket wheel since the force exerted by the spring 146 is largest at this point. This gives the maximum tooth strength where it is needed most.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. In a casting device including a fishing rod having a handle pivotally secured thereto, means to supply a fishing line, means to confine said line to a path extending along said rod, said rod being pivotable relative to said handle between a cocked position and a rest position, and means biasing said rod to the rest position for the purpose of casting the fishing line passing from the handle along the rod, clamping means for gripping the line in the cocked position, said clamping means including a pair of clamping members mounted for relative movement on one of said handle and rod elements, said line passing between said clamping members, cam means carried by one of said rod and handle elements and cam follower means carried by the other of said rod and handle elements coacting on pivotal movement of said rod relative to said handle to move said clamping members into and out of compressive engagement with the line such that the line is clamped in the cocked position and free of the clamping members in the rest position.

the clamping members in the rest position.

2. The casting device according to claim 1 wherein said cam follower means has lost motion on said cam means operating to delay release of said line as the rod moves away from the cocked position.

3. A casting device including a fishing rod element and a handle element pivotally secured thereto, said rod element being pivotable relative to said handle element between a cocked position and a rest position, means biasing the rod element to the rest position, fishing line supply means mounted on said handle element to supply line extending along said rod element, and means for gripping the line in the cocked position of said rod element and releasing the line on approach of the rod element to the rest position, said gripping means comprising a pair of clamping members mounted one fixedly and one movably on one of said rod and handle elements, said line passing between the clamping members, a cam element secured to the other of said rod and handle elements, an actuator responsive to said cam element for positioning said movable clamping member, and means biasing said actuator against said cam element, said cam element and said actuator cooperating to move said movable clamping member into and out of engagement with said fixed clamping member to clamp and release said line as the rod element pivots relative to the handle element.

4. The casting device according to claim 3 wherein said cam element is spaced from said actuator when said rod element is in the cocked position such that said clamping members remain in line clamping engagement during a fixed increment of pivotal movement of said rod element toward the rest position.

5. In a casting device including a fishing rod having

a handle pivotally secured thereto, means supplying a line passing along said rod, said rod being pivotable relative to said handle between a cocked position and a rest position, and means biasing said rod to the rest position, clamping means to clamp the line in the cocked position, said clamping means including a flexible tube supported by one of said handle and rod elements, said line passing through said tube, and cam means coacting between said handle and rod elements on pivotal movement thereof to kink said tube such that the line passing therethrough is clamped in the cocked position and freed in the rest position.

6. A casting device comprising a handle, means to supply a fishing line mounted on said handle, rotary means including a fishing rod portion supported by the handle for rotation relative thereto, said line extending from said supply means along said rod portion, said rod portion extending substantially radially relative to the axis of relative rotation, yielding means biasing said rotary means in a predetermined direction of rotation, means coacting between said handle and said rotary means to provide a stop for limiting the rotation of said rotary means in the direction of bias, said rotary means being rotatable away from said stop against the bias of said yielding means to a cocked position, a latch mechanism coacting between said handle and said rotary means to releasably retain said rotary means in a cocked position, and line clamping means operating in response to rotation of said rotary means to clamp said line when said rotary means is in the cocked position and to release said line as the rotary means moves toward said stop, said line clamping means including a flexible tube supported by one of said handle and rotary means, said line passing through said tube, and means to kink and simultaneously compress said tube to thereby clamp said line, said last named means including a cam and cam follower coacting between said handle and said rotary means, said cam follower operating in response to rotation of said rotary means to kink said tube and compress said line as said rotary means moves to a cocked position and to release the kink in said tube so as to free said line as the rotary means moves toward said stop.

7. In a casting device including a rod and a handle pivotally secured thereto, said rod being pivotable relative to said handle between a cocked position and a rest position, means yieldingly urging said rod to pivot to said rest position, line supply means mounted on said device to supply a line, means confining said line to a path, a portion of which extends along said rod, gripping means mounted on said device adjacent said path for gripping said line, said line in said path passing through said gripping means, and means responsive solely to pivotal movement of the rod relative to the handle for actuating said gripping means to grip said line as the rod pivots from the rest position toward a cocked position and for releasing said line as the rod moves from the cocked position to said rest position.

8. A casting device comprising a handle, means to supply a fishing line mounted on said handle, rotary means including a fishing rod portion supported by the handle for rotation relative thereto, means to confine said line to a path extending from said supply means along said rod portion, said rod portion extending substantially radially relative to the axis of relative rotation, yielding means biasing said rotary means in a predetermined direction of rotation, means coacting between said handle and said rotary means to provide a stop for limiting the rotation of said rotary means in the direction of bias, said rotary means being rotatable away from said stop against the bias of said yielding means to a cocked position, a latch mechanism coacting between said handle and said rotary means to releasably retain said rotary means in a cocked position, line clamping means mounted on said device adjacent said path for clamping said line, said line in said path passing through said clamping means, and means

5 operating solely in response to rotation of said rotary means for actuating said line clamping means to clamp said line in said path when said rotary means is in the cocked position and release said line as the rotary means moves toward said stop.

9. A casting device according to claim 8 wherein said line clamping means includes a pair of clamping members mounted for relative movement on one of said handle and rotary means, said line passing between said clamping members, and wherein said means to actuate said line clamping means includes cam means coacting between said handle and rotary means on pivotal movement thereof to move said clamping members into and out of compressive engagement such that the line is clamped in the cocked position and is freed from the clamping members as the rotary means moves toward the rest position.

10. A casting device according to claim 9 wherein one of said clamping members includes a loop portion through which said line passes, said clamping members having 15 relative movement for positioning said loop portion adjacent the other of said clamping members to clamp said line, said line passing freely through said loop portion when freed by said clamping members.

11. A casting device comprising a handle, means to supply a fishing line mounted on said handle, rotary means including a fishing rod portion supported by the handle for rotation relative thereto, means to confine said line to a path extending from said supply means along said rod portion, said rod portion extending substantially 25 radially relative to the axis of relative rotation, yielding means biasing said rotary means in a predetermined direction of rotation, means coacting between said handle and said rotary means to provide a stop for limiting the rotation of said rotary means in the direction of bias, said rotary means being rotatable away from said stop against the bias of said yielding means to a cocked position, a latch mechanism coacting between said handle and said rotary means to releasably retain said rotary means in a 30 cocked position, and line clamping means operating solely in response to rotation of said rotary means to clamp said line when said rotary means is in the cocked position and to release said line as the rotary means moves toward said stop, said line clamping means including a flexible tube supported by one of said handle and rotary means, said line in its path passing through said tube, and including means to kink and simultaneously compress said tube to thereby clamp said line, said last named means including a cam and cam follower coacting between said handle and rotary means, said cam follower operating in response to rotation of said rotary means to kink said tube and compress said line as the rotary means moves to a cocked position and to release the kink in said tube so as to free said line as the rotary means moves toward said stop.

12. In a casting device including a fishing rod and a handle pivotally secured thereto, said rod being pivotable relative to said handle between a cocked position and a rest position, fishing line supply means mounted on said device to supply a line, means confining said line to a path extending along said rod, gripping means mounted 55 on said device adjacent said path to grip said line, said line in said path passing through said gripping means, and means responsive solely to pivotal movement of the rod relative to the handle for actuating said gripping means to grip the line in said path as the rod pivots from the rest position toward a cocked position and to release said line as the rod moves from the cocked position to the rest position, said gripping means including a pair of relatively movable clamping members positioned on said device along the path of said line between said supply means and the outer end of said rod for clamping upon said line, the improvement wherein said line has a bulge thereon located a distance from the end of the line at least as great as the maximum separation between the outer end of said rod and said clamping members, the construction and arrangement being such that said bulge prevents 60 65 70 75

movement of the line through the clamping members when the latter are in position to grip the line.

13. The improvement according to claim 12 wherein said clamping members each include a loop portion, said clamping members having relative movement for positioning said loop portions side by side, said line and said bulge passing freely through one of said loop portions, said loop portions when disposed in side by side relation having aligned inner margins which cooperate to confine said bulge and thereby secure said line.

14. A casting device including a fishing rod and a handle pivotally secured thereto, said rod being pivotable relative to said handle between a cocked position and a rest position, fishing line supply means mounted on said handle to supply a line, means to confine said line to a path extending along said rod, a leader knotted to the end of said line, gripping means mounted on said device adjacent said path to grip said line in said path, and means responsive solely to pivotal movement of the rod relative to the handle for actuating said gripping means to grip the line as the rod pivots from the rest position toward a cocked position and to release the line as the rod moves from the cocked position toward the rest position, said gripping means including relatively movable clamping members positioned on said device along the path of

said line between said supply means and the outer end of said rod for clamping upon the line, said line in said path passing through said gripping means, the improvement wherein said leader has a length exceeding the distance between said clamping members and the outer end of said rod whereby the knot between said leader and said line may be positioned between said clamping members and said line supply means upon the line being drawn into the supply means, said clamping members and said knot cooperating to prevent withdrawal of the line from said supply means upon operation of said gripping means.
